Specification for Design.

Patented Dec. 7, 1915.

Application filed October 7, 1915. Serial No. 54,677. Term of patent 3½ years.

To all whom it may concern:

Be it known that I, HENRY SCHWARBER, a citizen of the Republic of Switzerland, residing at Weehawken, in the county of Hudson and State of New Jersey, have invented a new, original, and ornamental Design for Embroidered Lace, of which the following is a specification, reference being had to the accompanying drawing, forming part thereof.

The figure is a plan view of a portion of embroidered lace showing my new design.

I claim:

The ornamental design for an embroidered lace as shown.

HENRY SCHWARBER.
